UNITED STATES PATENT OFFICE

HANS C. HANSON, OF ALBERT LEA, MINNESOTA
GASOLINE COOKING STOVE WITH TORCHLESS STARTING

Application filed May 19, 1926. Serial No. 110,095.

This invention relates to a stove adapted to use liquid vaporizing fuel such as gasoline. As is well known to those skilled in the art, such stoves are now used in large numbers for various cooking and heating purposes. In such stoves it is necessary to preliminarily heat the vaporizing member into which the liquid fuel is sprayed in a fine jet, before the stove can be placed in operation. This vaporizing member has heretofore been heated either by a torch using some such fuel as alcohol, or by means of a priming cup carried on the stove and disposed beneath the vaporizing member into which a small quantity of gasoline was placed and ignited.

It is an object of the present invention to provide a starting means for a stove using liquid vaporizing fuel, with the use of which the stove can be started by merely supplying a small flame, such as that made by the burning of an ordinary match, thereto.

It is a further object of the invention to provide such a stove having a burner, a fuel tank and a conduit connecting the burner and fuel tank including a vaporizing member, together with a small auxiliary burner disposed beneath or in proximity to the vaporizing member, which auxiliary burner can be started by merely momentarily applying a small flame thereto such as the flame created by burning an ordinary match.

It is still another object of the invention to provide a stove adapted to use liquid vaporizing fuel having a burner, a fuel tank, a conduit connecting the burner and tank including a vaporizing member, said conduit including a portion having therein a thermostatically operated valve together with a preliminary heating means adapted to be ignited by the application of a small flame such as that created by burning an ordinary match, said heating means being disposed adjacent said vaporizing tube and said portion of said conduit.

These and other objects and advantages of the invention will be fully set forth in the following description made in connection with the accompanying drawings, in which like reference characters refer to similar

parts throughout the several views and in which—

Fig. 1 is a plan view of a stove embodying the present invention;

Fig. 2 is a view in front elevation thereof; 55

Fig. 3 is a view in end elevation of a stove, some portions being broken away;

Fig. 4 is a vertical section taken on line 4—4 of Fig. 1; and

Fig. 5 is a vertical section taken substantially on line 5—5 of Fig. 1.

Referring to the drawings, a stove is shown and while the invention is applicable to any type of stove using liquid vaporizing fuel, in the embodiment of the invention illustrated the stove shown is of a type adapted for use in domestic cooking, as for a kitchen stove. The said stove comprises a frame having legs 10 arranged at the corners of a rectangle and formed of angular pieces of sheet metal, said legs having other angle members 11 at their lower ends having bottom plates forming the supports for said legs. End and rear plates 12 and 12^a respectively are secured to the corner members 10 and extend therebetween substantially from the top of said corner members to a short distance from the lower ends thereof and a top plate 13 is bolted to portions extending inwardly from the rear plate and 70 an angle member 14 extending across the tops of the front leg members 12. The top plate 13 has a pair of spaced openings 13^a therein having outwardly extending ledges 13^b at their sides disposed some distance below the top surface of the plate 13 and adapted to support suitable grids (not shown). The end walls 12 have plates 15 extending downwardly at an angle from their inner sides carrying supporting means 16 forming guides 20 for a catch pan 17 which is slidable in said guides and removable at the front of the stove between the legs 10. A channel brace member 18 also extends between the front legs 10 a short distance from the bottoms 95 thereof.

A burner manifold 19 extends longitudinally of the frame substantially centrally thereof, and has supporting lugs 19^a at its top secured to the top plate 13 by the screws 100

20. The manifold has a burner 21 at each end thereof and intermediate the burners has a mixing chamber 19^b having an air opening in one side thereof which can be varied in size by an adjustable gate or valve member 22. One of the burners 21^a is equipped with a regulating valve having a stem 23 extending to the front of the stove and having a hand wheel 24 at its end, said stem being supported by an angle bracket 25 secured to the channel member 14. The manifold 19 has a fuel receiving portion 19^c having an open end into which fits the inner end of a vaporizing tube 26, said tube extending through one end wall 12 of the frame. The tube 26 has a valve formed therein controlling the flow of fuel to the manifold 19 which valve is formed on the end of stem 27 having an operating hand wheel 27^a at its outer end.

20 The tube 26 is supported at its outer end by a coupling member 28 having a lug secured to the outer side of the end plate 12. The coupling member has a tube extending downwardly therefrom from which extend laterally at each side the tubes 29 and 29^a respectively. The tube 29 extends to a coupling member 30 disposed over and adjacent one end of the fuel tank 31. The fuel tank 31 is disposed at one end of the frame outside of 30 and substantially in contact with the end plate 12 and is secured to said end plate by a pair of brackets 32. Said tank is thus permanently secured to the frame and said tank is equipped with a filling plug 31^a. The coupling member 30 is secured to and communicates with the interior of the tank and has an outwardly projecting portion in which is secured a valve having an outwardly projecting valve stem carrying the operating hand wheel 33. A torsion spring 34 surrounds the stem of said valve and has one end secured in the wheel 33, and its other end secured to an arm projecting forwardly from the coupling member 30. The valve operated by the wheel 33 closes the opening into the conduit 29 and the spring 34 normally turns the wheel 33 so that said valve is held tightly in closed position. The coupling member 30 has a pressure gauge 35 secured at one side thereof constructed and arranged to indicate the air pressure which is placed on the fuel in the tank 31. The coupling member 30 also has a valve formed therein adapted to shut off the passage of gasoline from the tank 31 which valve is formed on an upwardly extending stem 36 and operated by the key or wing handle 37. A tube 38 extends from the inner side of the coupling member 30 around the outer side of the end plate 12 and rear plate 12^a and is connected at its other end to the end of the plug member 39 secured in a tube 40 which tube 40 extends through the rear end 12^a and transversely of the frame substantially at right angles to the longitudinal center line thereof. The tube 40 has a plug 41 secured in its other end into which is threaded another tube 42 which is threaded at its other end into a coupling member 43. The coupling member 43 is threaded at its other end to receive a cap 44 and has an interiorly threaded recess in said end receiving a threaded plug 45. The members 39 to 43 preferably are formed of brass or other metal with a high coefficient of expansion. A steel rod 46 extends through the members 40, 41, 42, 43 and 45 and has a slotted end projecting from said latter member and disposed within the cap member 44. The rod 46 has secured thereto at its other end a cup shaped sleeve 47 into which is secured a conical valve 48. The valve 48 co-operates with a conical valve seat formed in the inner end of plug 39 and from the center of which a small aperture 39^a leads through the member 39 and thus communicates with the tube 38. A coil compression spring 46^a surrounds the stem and this engages the sleeve 47 at one end and at its other end said spring engages a nut 49 threaded onto the rod 46. The coupling member 43 extends through the angle member 14 at the front of the frame and is secured thereto. Said coupling member 45 has a laterally extending nipple 45^a to which is secured a tube 50 having a sleeve 51 at its other end in the ends of which are secured the tubes 29^a and 52 respectively. The tube 52 extends substantially parallel to the front of the frame and is coupled at its other end to a coupling member 53 having lugs 53^a bolted to the under side of the angle member 14. The coupling member 53 has a valve therein adapted to cut off communication with tube 52, which valve is formed on the valve stem 54 having at its outer end an operating wheel 55. The tube 56 extends from the inner end of the member 53 and into a Bunsen casing 57 having a passage or mixing chamber extending reversely from the end of the tube 56 and having an open end directed upwardly beneath said tube. The member 57 is carried on a rod 58 secured to a lug depending from the member 53. As shown in Figs. 1 and 4, the upwardly directed opening in member 57 is disposed beneath the vaporizing tube 26 and closely adjacent the underside of the tube 42. Casing 57 has an air inlet opening 57^a.

In operation fuel will be placed in the tank 31 and placed under considerable air pressure. The connection of the tank with the coupling member 30 extends to a point adjacent the bottom of the tank and gasoline is thus forced up into the coupling member 30. When the stove is entirely new and has not been previously operated, the valve wheel 33 will be turned momentarily against the pressure of spring 34 to open said valve and allow some gasoline to be forced through the tubes 29 and 29^a into the tube 52 and member 53. The valve 48 normally is closed and

is always closed when the tubes 40 and 42 are at low temperature. The gasoline thus cannot pass this valve. After the valve wheel 33 has been opened a few seconds it is released and the valve controlled thereby again allowed to close. The operator now takes a match and holds the burning match under the tube 56. This tube is sufficiently heated by a very small flame such as that produced by an ordinary burning match being disposed under the same a few seconds, so that the gasoline is vaporized and hand wheel 55 is then turned to open the valve 54 and the vapor generated in tube 56 is projected into the passage in member 57. Air is drawn in through opening 57^a and a combustible mixture issues through the open end of passage 57 which is directed upwardly beneath the tube 56 and tube 26. A Bunsen flame is thus formed and plays upwardly upon tube 56 and tube 26 and very close to tube 42 so that these tubes are heated. The combustible mixture issuing from the member 57 is ignited by the same match used to heat the tube 56. The hand wheel 27 is now operated to open the valve in tube 26 which controls the flow of fuel to the manifold 19. No fuel, however, can flow to this manifold as such fuel must come through the tube 28 and tubes 40 and 42. This line is closed, however, by the valve 48. The hand wheel 27^a therefore can be turned to open the valve in tube 26 and left in this position. The flame from member 57 will heat the tube 42 and said tube will expand at a considerably greater rate than the stem 46. The tube thus moves plug 39 away from valve 48 and said valve is opened. Gasoline can now flow through the tube 40 and plug 39 through the tube 42 into the tube 52 through sleeve 51 and tube 29^a upwardly into coupling member 28 and into the vaporizing tube 26. From the vaporizing tube it flows into the mixing chamber 19^b where it is mixed with air passing through the air opening in the manifold 19 and passes to the burner 21. The flame from the member 57 is sufficiently close to ignite the burner 21. No combustible mixture can flow to the burner 21^a until the hand wheel 24 is operated. When this is done, the burner 21^a can be separately ignited. The burner 21 now being ignited and in operation, the flame thereof can be regulated as desired by manipulation of the hand wheel 27^a and the hand wheel 55 can now be turned to close the valve 54 thus extinguishing the lighting flame at the member 57. The stove has thus been put in operation and ignited merely by using an ordinary match or a very small flame for a very few seconds. The stove being now as described the hand wheel 33 is initially operated. After the stove has once been operated, however, there is always sufficient fuel remaining in the tubes leading to the member 53 so that it is unnecessary to operate the valve 33. All that is necessary is to open valve 54 by turning wheel 55 and apply the match beneath the tube 56. When the burners are extinguished by manipulation of the hand wheels 27^a and 24, the tubes 42 and 40 will again contract so that valve 48 will again be closed. The spring 46^a is provided so that in case the device is taken into very low temperatures and the tubes 42 and 40 would contract greatly, the valve seat and valve would not be injured by excessive pressure. If this should occur the spring 46^a would yield and thus protect the valve and valve seat.

When the burners are extinguished by manipulation of the hand wheels 24 and 27^a, the tubes 42 and 40 will contract and valve 48 will be closed so that the fuel line will then be closed and will not be opened until tubes 42 and 40 are again heated. It will thus be seen that should the burners be accidentally extinguished without closing the valves on valve stems 23 and 27, that the tubes 42 and 40 would soon cool and close the fuel line by the valve 48.

From the above description it is seen that applicant has provided a very simple, efficient and convenient stove for using liquid vaporizing fuel. The necessity for attention to the stove for several minutes in lighting the stove is eliminated. The valve controlling the vaporizing tube can be opened and the small burner started in a few seconds and the stove can then be left until the burner 21 is in operation. The operator then needs only to extinguish the small lighting burner. The device has been amply demonstrated in actual practice and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. A stove adapted to use liquid vaporizing fuel having in combination, a main burner, a fuel tank, a conduit connecting the burner and tank including a vaporizing member a manually operated control valve and a thermostatic valve in said conduit between said vaporizing member and tank adapted to be opened when said conduit is heated, a small auxiliary burner comprising a mixing chamber, a conduit connecting said auxiliary burner to said fuel tank comprising a mixing chamber and a quite small generating tube, said auxiliary burner being disposed beneath the portion of said conduit in which said valve is disposed whereby said small auxiliary burner will heat said conduit and automati-

cally cause said thermostatic valve to open whereby fuel may flow to said vaporizing tube.

2. A stove adapted to use liquid vaporizing fuel having in combination, a fuel tank, a main burner, a conduit connecting said burner and fuel tank including a vaporizing tube, a manually operable valve in said vaporizing tube for shutting off and controlling the supply of fuel to said burner, said conduit including a tube having therein a valve which is normally closed but adapted to be operated to supply fuel to said burner when said last mentioned tube is heated, a small auxiliary burner of Bunsen type having a mixing chamber disposed in close proximity to both of said tubes and a conduit connecting said auxiliary burner to said fuel tank including a very small generating tube which can be heated to start said auxiliary burner by a very small flame such as that produced by an ordinary match and a manually operated valve controlling said last mentioned conduit.
3. A stove adapted to use liquid vaporizing fuel having in combination, a fuel tank, a burner, a mixing chamber to which said burner is connected, a vaporizing tube connected to said mixing chamber, a valve in said vaporizing tube for shutting off and controlling the supply of fuel to said mixing chamber, a conduit connecting said vaporizing tube to said fuel tank, a valve in said conduit normally closed but adapted to be opened when said conduit is heated, a small auxiliary Bunsen burner disposed beneath said vaporizing tube and between said burner and mixing chamber in proximity to said conduit, a conduit connecting said auxiliary burner to said fuel tank including a very small generating tube which can be heated to start said auxiliary burner by a very small flame such as that produced by an ordinary match.

In testimony whereof I affix my signature.
HANS C. HANSON.
